DESIGN.

—o—
J. A. PRICE.
HEATING STOVE.

No. 18,837.

Patented Jan. 1, 1889.

UNITED STATES PATENT OFFICE.

JOHN A. PRICE, OF SCRANTON, PENNSYLVANIA.

DESIGN FOR A HEATING-STOVE.

SPECIFICATION forming part of Design No. 18,837, dated January 1, 1889.

Application filed June 9, 1888. Serial No. 270,050. Term of patent 14 years.

To all whom it may concern:

Be it known that I, JOHN A. PRICE, of Scranton, in the county of Lackawanna and State of Pennsylvania, have invented a new and original Design for a Heating-Stove, of which the following is a specification, reference being had to the accompanying photograph, representing a perspective view of a stove embodying my said design.

10 In the production of the design my object has been to artistically represent the different portions of the Indian corn or maize plant upon the several parts. In carrying out this object I have represented on the panels A of 15 the movable top of the stove a series of ears of corn, *a*, alternating with a series of stalks having leaves and tassels, as shown at *b*.

The vertical corners C of the stove represent stalks, and the moldings D and E, near 20 the top and near the center of the stove, respectively represent ears partially enveloped by leaves, *d* representing the ears and *d'* the leaves on the moldings D, and *e* and *e'* the ears and leaves, respectively, on the molding E, as shown. The base F, on its rounded corners F', bears the representation of partly-formed ears, while the legs G represent a combination of roots, *g*, lower portions of stalks, *g'*, and leaves *g''*, as shown. The upper doors, H, are formed with the representation of a 30 row of grains of corn, *h*, around their margins and with the representation of twisted leaves *z* as a frame-work for holding the mica. On the doors I, opposite the fire-pot, are represented a series of open ears, *i*, and on the door K, leading to the ash-pit, a series of full stalks, *k*, with leaves, are shown.

Having thus described my invention, what I claim as new is—

1. The design for a heating-stove consisting 40 in the top having the panels with the representation of the series of ears of corn alternating with the series of stalks provided with leaves and tassels, as described and shown.

2. The design for a heating-stove consisting 45 in the body having the corners representing upright stalks of corn and the horizontal ornamental moldings representing ears of corn partially enveloped in corn-leaves, as shown and described. 50

3. In a design for a heating-stove, the upper ornamental open-work doors representing rows of grains of corn around the edges, and cross-bars representing twisted corn-leaves, as described and shown. 55

4. In a design for a heating-stove, the fire-pot doors with the representation of the partially-opened ears of corn projecting into the open spaces, substantially as shown.

5. The design for a heating-stove herein described and shown, consisting in the body with the representations of upright stalks of corn thereon, and the horizontal ornamental moldings representing ears of corn partially enveloped in leaves, the top having the panels with the representation of the series of ears of corn alternating with the series of stalks provided with leaves, the upper doors and the fire-pot doors having the representations of corn thereon, as shown and described. 60 65

JOHN A. PRICE.
